UNITED STATES PATENT OFFICE.

MILTON H. SHOENBERG AND GEORGE J. HENRY, OF SAN FRANCISCO, CALIFORNIA,
ASSIGNORS TO MAJESTIC ELECTRIC DEVELOPMENT COMPANY, OF SAN FRAN-
CISCO, CALIFORNIA, A CORPORATION OF CALIFORNIA.

DESIGN FOR AN ELECTRIC HEATER.

55,336.

Specification for Design.

Patented May 25, 1920.

Application filed September 16, 1919. Serial No. 324,253. Term of patent 14 years.

To all whom it may concern:

Be it known that we, MILTON H. SHOENBERG and GEORGE J. HENRY, citizens of the United States, and residents of the city and county of San Francisco, State of California, have invented a new, original and ornamental Design for Electric Heaters, of which the following is a specification, reference being had to the accompanying drawings, forming a part thereof.

Figure 1. is a plan view of our heater.

Fig. 2. is a side view of our heater.

We claim:

The ornamental design for an electric heater substantially as shown.

In testimony whereof, we have hereunto set our hands at San Francisco, California.

MILTON H. SHOENBERG.
GEORGE J. HENRY.

In presence of—

P. S. PIDWELL.
